CLAIM

USPC D10/96-103, 46, 47, 85, 86, 80-82,

The ornamental design for a digital dial gauge, as shown and described.

DESCRIPTION

D10/75-79, 61, 65, 67, 106.91, 106.9,
D10/106.4

FIG. 1 is a front, left-side, top perspective view of the digital dial gauge;

CPC G01D 5/2415; G01D 13/00; G01D 13/10;

FIG. 2 is a front elevational view thereof;

G01D 11/24; G01B 5/207; G01B 3/22;

FIG. 3 is a rear elevational view thereof;

G06F 7/4983; G06F 3/04842; G06F

FIG. 4 is a left-side elevational view thereof;

15/0275; G06F 3/03545; G06F 3/0482;

FIG. 5 is a right-side elevational view thereof;

G06F 3/04847; G01L 19/14; G01L

FIG. 6 is a top plan view thereof; and,

19/0023; G01L 19/143; G01L 19/0092;

(Continued)

G01L 19/086; Y10S 33/06; G09G

2340/145; G01F 1/26; G01F 23/02; G01F

1/28; G01F 1/05; G01F 15/06; G01F

23/0015; G01F 1/22; G01F 1/06; G01F

FIG. 7 is a bottom plan view thereof.

The broken lines depict parts of the digital dial gauge that form no part of the claimed design.

1 Claim, 7 Drawing Sheets
